UNITED STATES PATENT OFFICE.

LOUIS E. RODGERS, OF CHICAGO, ILLINOIS.

RAIL-CLIP.

No. 813,738.

Specification of Letters Patent.

Patented Feb. 27, 1906.

Application filed November 17, 1905. Serial No. 287,815.

To all whom it may concern:

Be it known that I, LOUIS E. RODGERS, a citizen of the United States, residing at Chicago, in the county of Cook and State of Illinois, have invented a new and useful Improvement in Rail-Clips, of which the following is a specification.

My invention relates to improvements in the construction of clips for securing railway-rails to metal ties or structural-steel beams which are formed with top flanges or shoulders; and my object is to provide a clip of peculiarly simple and inexpensive construction capable of being readily and quickly applied.

One particular field of usefulness for my improved clip is in brick-drying tunnels for securing T-rails to the I-beams which extend across the bases of the tunnels.

In the drawings, Figure 1 is a partly sectional fragmentary view showing my improved clip employed as a means for fastening a T-rail to an I-beam; Fig. 2, a broken and partly-sectional top plan view; and Figs. 3 and 4, broken partly-sectional views illustrating, respectively, the opposite ends or sides of the clip.

A is an I-beam forming a tie on which the T-rail B rests.

My improved clip consists of a side or end piece C, a clamping-head D, and a connecting-bolt E, provided with a nut F.

The part C comprises a bar a, formed at one end with a large upward-extending boss b and at its opposite end with a small upward-extending boss c. Extending from end to end of the part C at its inner side is a slightly-flaring groove or recess d, and the boss c is provided on its inner side coincidentally with the upper edge of the bar portion a with a groove or recess e, which flares transversely, as shown by full lines in Figs. 3 and 4. The base of the recess e, as well as the edge portion of the boss, is inclined to extend in planes nearly, but not quite, at right angles to the sides C of the part, as indicated by the line f and dotted line g in Fig. 2, whereby the rail-seating face h of the part C is rendered slightly flaring. The boss b is provided with an opening i through it of tapering form, as indicated in Fig. 2. The clamping head or part D is larger than, but of much the same shape as, the boss portion b and is provided with a tapering opening

through it, k. In one side of the head D is a flaring recess l, and in its inner face is a transversely-flaring and longitudinally-tapering recess m.

To fasten the rail B to the beam A, the part C is passed beneath the rail, hooked at its recess e over one side flange of the rail, 60 and swung upward to the position shown in Fig. 3. The surface h of the part C should be of a length just capable of receiving the base of the rail, so that the latter will be pressed at opposite edges, respectively, by 65 the inner surface of the boss b while engaged by the recessed portion of the boss c. The part C is then slid laterally to cause its groove d to pass over the adjacent edge of the I-beam A, as indicated in Fig. 1. The part or 70 head D is then passed at its groove m over the opposite edge of the I-beam and at its groove l into engagement with the flange of the rail. When the parts are in the position described, the openings i k are in line and in 75 a plane just above the surface of the I-beam, the flaring ends of the openings i k being adjacent to each other. The bolt E is passed through the coincident openings i k, as indicated in Fig. 2, and the nut F is applied to 80 the bolt to tighten the parts together. The engagement of the grooves m d with the I-beam causes the clip to be fastened rigidly in place, and the engagement of the clip at its grooves e l with the flanges of the rail B 85 fastens the latter rigidly upon the surface of the I-beam. The flaring nature of the recesses causes them to conform to and grip the flanges over which they are passed, and the flaring nature of the openings k i, coupled 90 with the inclination of the bases of the recesses e l, permits the clip to conform to slight variations in angle between or unevennesses in the rail and I-beam flanges.

Hitherto it has been the common practice 95 to fasten T-rails to I-beams with bolts passing through openings in their flanges. These openings had to be drilled, making the operation of laying the rails necessarily slow and laborious. My improved clips, on the other 100 hand, may be applied very quickly and when in place fasten the rails with great security.

What I claim as new, and desire to secure by Letters Patent, is—

1. In a rail-clip, the combination of two 105 separate metal parts provided with coinci-

dent bolt-openings and each having recesses for engaging flanges of both the rail and tie, and a bolt passing through said openings with means thereon for tightening the parts in clamping engagement with the rail and tie.

2. In a rail-clip, the combination of two separate metal parts provided with coincident bolt-openings and with flaring recesses inclined one with relation to the other fitting and engaging the flanges of both the rail and tie, and a bolt passing through said openings with means thereon for tightening the parts in clamping engagement with the rail and tie.

3. In a rail-clip, the combination of two separate metal parts provided with coincident flaring bolt-openings and flaring and inclined recesses fitting and engaging flanges of both said rail and tie, and a bolt passing through said openings with means thereon

for tightening the parts in clamping engagement with the rail and tie.

4. In a rail-clip, the combination of a metal part comprising a bar having an upper surface to bear against the under surface of the rail, a longitudinally-extending recess in one side to engage a flange of the tie, a boss having a recess to engage a flange of the rail and a boss provided with a bolt-opening, a separate metal part having a bolt-opening and recesses, one of which engages a flange of the tie and the other a flange of the rail, and a bolt passing through said openings with means thereon for tightening the parts in clamping engagement with the rail and tie.

LOUIS E. RODGERS.

In presence of—

J. H. LANDES,
A. U. THORIEN.
